UNITED STATES PATENT OFFICE.

NATHAN E. NEWMAN, OF BRONXVILLE, NEW YORK.

PLASTIC SHEET OR SLAB.

Application filed March 5, 1926. Serial No. 92,440.

My invention relates to a new article of manufacture in the nature of a sheet or slab constructed or formed for the purpose of imitating tiling, to an improved process for producing the same.

The body of the slab consists of an admixture of asbestos and cement, the cement being employed as a binder. After the slab has been formed and comes from the molding machine, and is thoroughly dry, it is provided with a multiplicity of intersecting scores and subsequently the surface which has been scored is treated with an application of nitrocellulose.

15 In the drawings:

Figure 1 is a perspective view of one of the slabs embodying my invention; and

Figure 2 is a cross section thereof.

Referring more particularly to the drawings, the numeral 5 designates the body of the slab consisting of an admixture of asbestos and cement, the cement serving as a binder for the asbestos fibers. The slab in its entirety is produced by any suitable molding process, and after it has indurated it is scored in criss-cross fashion as shown at 6 to imitate tiling. In this connection, I wish to point out that it is extremely important that the recesses or kerfs be formed in the body of the slab after it has been molded and indurated, as if it is attempted to impress the kerfs in the admixture while it is in a plastic state, it will be found that they will not register when the slabs are set up, obviously due to contraction of the mass.

When the slab has been scored the obverse side thereof is coated with nitrocellulose 7 which not only serves to protect the body, but produces an effect very closely imitating real tiling.

What I claim is:

1. The improved process of producing artificial slabs which consists in first mixing asbestos and a binder, then molding therefrom an indurated slab, scoring the face of 45 the indurated slab, and then providing the scored face with a protective coating.

2. As an article of manufacture, a slab consisting of an indurated admixture of asbestos and a binder provided with intersecting scores extending along the complete 50 expanse of said body, and a protective covering for the surface of said slab which is scored.

3. As an article of manufacture, a slab 55 consisting of an indurated admixture of asbestos and a binder provided with intersecting scores, and a coating of nitro-cellulose over the obverse side of the body.

4. The improved process of producing artificial slabs which consists in first mixing asbestos and a binder, then molding and indurating a slab of said mixture, and scoring the wearing side of the indurated slab to produce a tile effect.

Signed at New York city, New York, this 6th day of February, 1926.

NATHAN E. NEWMAN.
